UNITED STATES PATENT OFFICE.

H. HUNT, OF DELAVAN, WISCONSIN.

IMPROVEMENT IN GATES.

Specification forming part of Letters Patent No. 76,920, dated April 21, 1868.

To all whom it may concern:

Be it known that I, H. HUNT, of Delavan, in the county of Walworth, in the State of Wisconsin, have invented a new and useful Improvement in Gates; and I do hereby declare that the following is a full and exact description thereof, reference being had to the accompanying drawings, and to the letters of reference marked thereon, making a part of this specification, in which—

Figure 1 is a longitudinal elevation of my improved gate; Fig. 2, a transverse sectional elevation of the same.

This invention relates to that class of gates which are arranged so that equestrians and those riding in carriages may open and shut them without alighting; and its nature consists in a gate hung on friction-rollers arranged to run on opposite sides of a concavo-convex track having sharp or thin edges conforming to the peripheries of the rollers, and a novel device for supporting the pulleys over which the cords for running the gate are made to pass.

To enable others skilled in the art to fully comprehend the construction and operation of my invention, I have marked corresponding parts with similar letters, and will now give a detail description.

A represents the ground, which is made to support a double post, C C, through which the gate is made to run; two posts, B B, for the support of the cords R in a convenient position to be reached from a carriage; a track-support, E, and a jamb-post, D, all of which are arranged similar to other gates of this class, except the double post C C, which is made to form a part of the box for pulleys S T, as seen at Figs. 1 and 2, and support the track J K. This track has a novel construction, and as follows: The cheapest plan is to use a piece of hard-wood plank, and cut the surplus edges away, so as to make long curves K K and a short curve, d, between, as seen at

Fig. 1, and then cover the edges on which the rollers M L run with strap or cast iron formed to suit grooves in the peripheries of said rollers.

The gate F has three posts, G H I, the two latter being used to support straps V V, rigidly attached to said posts, and having holes made through them, in which the pivots of rollers M L revolve. The double post C C is made to form a part of the box W, which supports the rollers T S, the latter being set parallel with gate F and the former transversely with it, and the cords R R, attached to the gate F at X, are made to pass over the rollers and pulleys N N and extend down to a convenient position to be reached from a carriage, weights being hung to said cords for keeping them in position in the usual manner.

By this means a cheap, convenient, and substantial gate is provided, and one which can be readily opened and shut by any person capable of pulling down fifteen or twenty pounds weight on cords R, and not liable to get out of order by snow and ice, as the sharp edges of the track will always cut its way clear on the rollers. It is understood that either of the cords R will open and shut the gate, it being only necessary to pull down on one cord to open it, and on the other to shut it after having passed through.

Having thus described my invention, what I claim, and desire to secure by Letters Patent, is—

1. The concavo-convex track J, arranged for the rollers M L to run on its opposite sides, in combination with straps V and gate F, substantially as and for the purpose set forth.

2. The combination of track J, cords R, straps V, pulleys S T, box W, and gate F, substantially as set forth.

H. HUNT.
